CLAIM

The ornamental design of a casing and mounting assembly for electronic devices, as shown and described.

DESCRIPTION

FIG. 1 is a front elevational view of a casing and mounting assembly;

FIG. 2 is a back elevational view thereof;

FIG. 3 is a front elevational view of FIG. 1; the casing and mounting assembly door ajar;

FIG. 4 is a back elevational view of FIG. 1; the casing and mounting assembly door ajar;

FIG. 5 is a fragmentary right perspective view of FIG. 1 with mounting assembly removed for clarity of disclosure; the casing and mounting assembly door ajar;

FIG. 6 is a fragmentary right elevational view of FIG. 1 with mounting assembly removed for clarity of disclosure; the casing and mounting assembly closed;

FIG. 7 is a fragmentary left elevational view of FIG. 1 with mounting assembly removed for clarity of disclosure; the casing and mounting assembly door ajar;

FIG. 8 is a fragmentary left elevational view of FIG. 1 with mounting assembly removed for clarity of disclosure; the casing and mounting assembly closed;

FIG. 9 is a top elevational view of FIG. 1; the casing and mounting assembly door closed;

FIG. 10 is a top elevational view of FIG. 1; the casing and mounting assembly door ajar;

FIG. 11 is a bottom elevational view of FIG. 1; the casing and mounting assembly door closed;

FIG. 12 is a bottom elevational view of FIG. 1; the casing and mounting assembly door ajar;

FIG. 13 is an exploded front view of FIG. 1; the casing and mounting assembly door ajar;

FIG. 14 is an exploded back view of FIG. 1; the casing and mounting assembly door ajar;

FIG. 15 is a partial back view of FIG. 1; the hinge component of the casing and mounting assembly door positioned in a first unbarred state; and,

FIG. 16 is a partial back view of FIG. 1; the hinge component of the casing and mounting assembly door positioned in a second unbarred state.

Broken line showing of structure is included for the purpose of illustrating portions of the "article" and forms no part of the claimed design.
